[57] **CLAIM**

The ornamental design for a document stand, as shown and described.

DESCRIPTION

FIG. 1 is a front perspective view of a document stand showing my new design, the broken line disclosure of a table being for illustrative purposes only;

FIG. 2 is a front elevational view thereof;

FIG. 3 is a rear elevational view thereof;

FIG. 4 is a right side elevational view, the left side being a mirror image thereof;

FIG. 5 is a top plan view thereof; and

FIG. 6 is a perspective view of a second embodiment of the document stand shown in FIG. 1.

FIG. 1

FIG. 2

FIG. 3

FIG. 5

FIG. 4

FIG. 6
